HEAT EXCHANGE APPARATUS

John P. Rathbun, Prospect Park, and Millard A. Nelson, Sharon Hill, Del., assignors to Westinghouse Electric & Manufacturing Company, East Pittsburgh, Pa., a corporation of Pennsylvania

Application June 30, 1943, Serial No. 492,822

4 Claims. (Cl. 257—32)

This invention relates to heat exchange apparatus of the vertical type, more particularly to vertical heat exchangers incorporating sub-cooling sections, and has for an object to provide improved apparatus of this character.

In order to obtain efficient operation of sub-cooling sections of heat exchangers, it is necessary to prevent leakage of steam to such section from the remaining portions of the heat exchanger, as such leakage of steam would raise the temperature of the condensate therein, thereby defeating the purpose of the sub-cooling section.

Therefore, another object of the invention is to provide, in vertical heat exchangers having a portion of the first water pass partitioned off as a sub-cooler, novel means for water-sealing the partition against leakage of gases therewith.

A further object of the invention is to provide novel means for preventing water hammer or similar unstable action in a vertical heat exchanger.

These and other objects are effected by the invention as will be apparent from the following description and claims taken in connection with the accompanying drawings, forming a part of this application, in which:

Fig. 1 is a vertical sectional view taken along the line I—I of Fig. 2, looking in the direction indicated by the arrows;

Fig. 2 is a transverse sectional view taken along the line II—II of Fig. 1, looking in the direction indicated by the arrows;

Fig. 3 is an enlarged fragmentary sectional view, taken along the line III—III of Fig. 1, looking in the direction indicated by the arrows;

Fig. 4 is a vertical sectional view of a modified construction, taken along the line IV—IV of Fig. 5, looking in the direction indicated by the arrows;

Fig. 5 is a transverse sectional view taken along the line V—V of Fig. 4, looking in the direction indicated by the arrows; and,

Fig. 6 is an enlarged fragmentary sectional view, taken along the line VI—VI of Fig. 4, looking in the direction indicated by the arrows.

Referring now to the drawings more in detail, particularly Figs. 1, 2 and 3, there is indicated in its entirety, by the numeral 10, a heat exchanger comprising a shell 11 having plurality of tubes 12 of U shape extending longitudinally thereof with their terminal portions extending into and supported by tube sheet 13, which forms a part of water box structure 14. The water box structure includes a vertically-disposed, diametrically extending partition 16 (Fig. 2), dividing the space

within the water box into an inlet chamber 17 having an inlet connection 18, and an outlet chamber 19 having an outlet connection 20, this chamber construction providing for flow of water through the tubes in a plurality of passes.

The shell 11 is provided with a steam inlet 22 and a condensate outlet 23. The lower end of the shell is closed by the water box structure 14 and the upper end by suitable structure, such as the dome 24, formed integral therewith or welded or bolted thereto. Preferably, the dome 24 is provided with suitable vent means, at 25, to assist in establishing circulation of steam through the apparatus. Also, there is provided an impingement baffle 26, extending in front of and in spaced relation to the steam inlet 22, to prevent injury to the tubes by the entering steam.

The space surrounding the coldest or lower portion of the tubes of the first water pass is partitioned off from the remaining space within the shell 11 to provide a sub-cooling section. This partition structure is formed by a vertical radially-extending partition 29 and a similar partition 30, together with a cooperating cross-corner partition 31 (Fig. 2). To provide for removal of this partition structure with the tube bundle, the partitions 29 and 30 are provided at their outer vertical edges with suitable sealing means 32, (Fig. 2), preferably of the Lamiflex type. This seal 32 performs the added function of preventing leakage of steam from the condensing space to the sub-cooling space.

It is seldom desired to use the entire length of the first water pass for a sub-cooling section, and, therefore, a horizontal partition, indicated in its entirety by the numeral 34, is provided at the upper limit of the sub-cooling section. As best indicated in Fig. 3, this partition 34 comprises upper and lower plates 35 and 36 respectively, having disposed therebetween a packing member 37. The horizontal partition 34 is sealed about its edges by upper and lower seal strips 38, held in place by pressure strips 39, the members 35, 36, 37, 38 and 39 being retained in assembled relation by suitable means, such as the bolts 40 and nuts 41. The horizontal partition 34 is provided with openings 44 therethrough for the passage of the tubes 12.

It will be noted that the horizontal partition 50 is positioned slightly below the upper edges of the radial partitions 29 and 30, with the result that the portions of these partitions extending above the horizontal partition 34 provide a dam structure, serving to retain on the horizontal 55 partition condensate flowing down or falling from

the portions of the tubes 12 extending thereabove. Condensate is collected on this horizontal partition to seal the clearance spaces between the tubes 12 and the openings 44 in the partition, against leakage of steam therethrough from the condensing space to the sub-cooling section, which leakage would occur due to the lower pressure existing within the sub-cooling section if the body of condensate was not maintained on the horizontal partition.

As best shown in Fig. 2, additional cross-corner partitions 45, 46 and 47 cooperate with the previously described cross-corner partition 31, to provide a square, centrally disposed, vertical conduit 48 extending from near the top of the shell to the bottom thereof. The partition 31 is provided with an opening 50 therethrough disposed just below the level of the upper ends of the radial baffles 29 and 30, thereby providing an overflow opening for discharge of condensate collecting on the horizontal partition 34. The condensate overflowing through the opening 50 passes downward through the conduit 48 to the bottom of the shell, where it passes out through the opening 52 in the tube plate 13, and through the passage 53 forming in the enlarged central section of the partition 16, for flow through the conduit 55 to the inlet connection 56 at the upper end of the sub-cooling section. Preferably, an impingement baffle 57 is disposed in spaced relation to the inner end of the inlet connection 56 to prevent damage of the tubes by the entering condensate. Also, there is preferably provided suitable vent means 58 for air and noncondensable gases at the upper end of the sub-cooling section in order that the latter may be maintained substantially full of condensate at all times.

To further insure of the sub-cooling section being maintained flooded throughout operation, there is provided, in the outlet connection 23 of the sub-cooling section, a flow-control valve 60, operated through linkage 61 by the float member 62, housed in the float container 63. This housing is connected by conduits 64 and 65 to the interior of the shell 11 and to the body of condensate within the shell, respectively. Thus, condensate is permitted to discharge from the sub-cooling section only when the volume of condensate within the shell reaches a predetermined level, thereby maintaining the sub-cooling section flooded.

As a result of the connections 64 and 65 between the chamber 63 and the interior of the steam space on the one hand and the condensate space on the other, the level of condensate in 63 will correspond with the level within or above the conduit 53, disposed centrally of the water box. With the subcooler outlet valve 60 closed, the condensate will fill the conduit 53, the conduit 55 leading therefrom, and the sub-cooling section in its entirety. It is possible to maintain these parts flooded with condensate even though the level of the latter in the chamber 63 is materially lower than portions of the flooded parts, due to the higher pressure existing at and above the condensate level within the shell and chamber 63 than exists at the outlet 23 of the subcooling section. As soon as the condensate level rises in the chamber 63, the consequent raising of the float 62 results in opening of the valve 60 to permit condensate to be forced through the conduits 53 and 55 and the subcooling section until the level in the shell and the chamber 63 has dropped sufficiently to cause the

valve float member 62 to return the valve 60 to closing position.

Inasmuch as the volume of the condensate which can be obtained from the condensing portions of the tubes of the first water pass overlying the horizontal partition 34, for maintaining said partition flooded, is frequently insufficient to satisfactorily seal the latter against leakage of steam therewith, this invention provides means for supplementing this supply of condensate. To this end, the shell 11 is provided with an inlet connection 68, positioned to discharge directly onto the horizontal partition 34 condensate returned from a separate higher pressure heat exchanger 69. Preferably, an impingement baffle 70 is provided to prevent damage to the tubes 12 by the entering condensate.

In order to provide for devious flow of the steam from the steam inlet 22, there are provided a plurality of horizontally disposed baffles 73 and 74, arranged in alternating, vertically-spaced relation and provided with openings 75 and 76, respectively, as best shown in Fig. 2. It will be seen that the openings 75 are located at the opposite ends from the openings 76 in the alternate baffles, with the result that devious flow of steam is insured.

To avoid water hammer or other unstable action resulting from counterflow of rising steam and falling condensate, the cross-corner partition 47 is provided with a plurality of openings 77, disposed adjacent the upper surfaces of the horizontal baffles 73 and 74, and through which condensate collecting on said baffles may flow to the vertical conduit 48, for passage to the bottom of the shell and thence to the sub-cooling section.

In Figs. 4, 5 and 6 there is illustrated a modification of the present invention wherein, instead of supplementing the sealing condensate, for the horizontal partition at the upper end of the sub-cooling section, by flashing condensate from an external source, there is provided means for collecting within a central vertical conduit, the condensate collecting on baffles disposed above the horizontal partition, and then directing this condensate from the central conduit to the horizontal partition to maintain the latter flooded.

Referring now to Figs. 4, 5 and 6, there is shown a heat exchanger, indicated in its entirety by the numeral 101, comprising a shell 102 having a steam inlet 103 and a condensate outlet 104. A plurality of tubes 105, extending vertically within the shell, have their terminal portions supported by a tube plate 106, forming a portion of a water box structure 107. The water box structure is divided into an inlet chamber 110 and an outlet chamber 111, the chambers having inlet and outlet connections 112 and 113, respectively, and providing for flow of water through the tubes in a plurality of passes.

The space within the shell 102 is bisected by a vertically-extending, diametrically-disposed partition 115. Radially-extending, vertically-disposed partitions 116 and 117 cooperate with the partition 115 to divide the space within the shell into quadrants. A pair of cross-corner partitions 118 and 119 cooperate with a supplementary radial partition 120 to provide a triangular central conduit 121, extending from a point near the top of the shell to the bottom thereof. The partitions 117 and 120 are preferably provided with Lamiflex seals at their outer edges in order that they may be withdrawn from the shell with the tube bundle.

The space enclosed by the partitions 117, 118 and 120 serves as a sub-cooling section, which has its upper limit determined by a horizontal partition, indicated in its entirety by the numeral 123. Comparison of Figs. 3 and 6 will show that the structure of the horizontal partition 123 (Fig. 6) is identical with that of horizontal partition 34 (Fig. 3), and, therefore, no detailed description of the partition 123 is deemed necessary.

The central partition 115 is provided at its lower edge with one or more openings 124 for passage of steam from the lower right-hand quadrant to the lower left-hand quadrant, as viewed in Fig. 5.

In order to provide for devous flow of steam through the apparatus, there are provided alternating horizontally-disposed baffles 125 and 126. The cross-corner partition 118 is provided with a plurality of openings 127 opposite the upper surfaces of the baffles 125 and 126, whereby condensate collecting on the latter may flow into the vertically-disposed central conduit 121. A barrier 128 is provided within the conduit 121 a short distance above the horizontal partition 123. An outlet opening 129 is provided in the partition 118 at the upper surface of the barrier 128, whereby condensate flowing down the central conduit 121 flows out through the opening 129 onto the horizontal partition 123 to maintain the latter flooded. A return inlet opening 130 is provided in the partition 118 slightly above the horizontal partition 123, in order that when the condensate on the partition reaches the level of said opening 130, it will flow therethrough back to the central conduit 121, for discharge through the passage 131 in the water box structure and the conduit 132, to the upper end of the sub-cooling section.

Discharge of condensate from the sub-cooling section is controlled by a discharge valve 133, operated through linkage 134, by the float 135 housed in the chamber 135a. This chamber is in communication with the interior of the shell and with the body of condensate in the shell, by conduits 136 and 137, respectively.

Preferably, the baffle 125 which overlies the shorter bundle of tubes is provided with a vent opening 138, and the shell dome is provided with vents 140 at each side of the diametric partition 118. Likewise, there is preferably provided a vent 141 at the upper end of the sub-cooling section.

Steam admitted to the shell through the inlet 103 (Fig. 5) rises through the northeast quadrant of the shell, crosses horizontally beneath the horizontal baffle 125 containing the vent 138 (Fig. 4), flows down through the southeast quadrant to the bottom of the shell where it crosses through the opening 124 in the partition 115 for upward flow through the southwest quadrant and thence across and down through the northwest quadrant until it reaches the horizontal baffle structure 123 at the top of the subcooling section.

While the invention has been shown in but one form, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. Heat exchange apparatus comprising a vertically-disposed shell having a steam inlet and a condensate outlet; a plurality of tubes extending vertically in the shell; means providing closures for the ends of the shell and including water box structure associated with the tubes and providing for flow of water therethrough in a plurality of passes; means separating the space surrounding the lower portions of the tubes of the first water pass from the remaining space in the shell, said means including a horizontal partition having openings through which said tubes extend, said separated space including the condensate outlet and constituting a sub-cooling section; means for conveying condensate from the bottom of said remaining space in the shell to the upper portion of the sub-cooling section; and means for water-sealing the sub-cooling section against leakage of steam thereinto through the clearance between the tubes and the walls of the openings in the horizontal partition through which said tubes extend, said last-mentioned means comprising a dam projecting above said horizontal partition adjacent the periphery thereon to retain thereon condensate formed on and flowing down the tubes in the condensing space thereabove, and means for supplementing the condensate thus collected on the horizontal partition for sealing purposes.
2. Structure as specified in claim 1, wherein the means for supplementing the condensate collected on the horizontal partition for sealing purposes comprises a conduit for introducing to the shell, at a point directly above said horizontal partition, condensate from a heat exchanger operating at higher pressure than exists in said shell.
3. Structure as specified in claim 1, wherein the means for supplementing the condensate collected on the horizontal partition for sealing purposes comprises a plurality of horizontally-disposed baffles spaced vertically within the shell at higher levels than said horizontal partition, a vertical conduit disposed in juxtaposition relation to said baffles and the horizontal partition and having openings therein adjacent the upper surfaces of the baffles for flow of condensate thereinto from said baffles, and means for directing onto the horizontal partition the condensate flowing in the conduit.
4. Structure as specified in claim 1, wherein the means for supplementing the condensate collected on the horizontal partition for sealing purposes comprises a plurality of horizontally-disposed baffles spaced vertically within the shell at higher levels than said horizontal partition; a vertical conduit disposed in juxtaposition relation to said baffles and to the horizontal partition and having openings therein adjacent the upper surfaces of the baffles for flow of condensate thereinto from said baffles; a barrier within the conduit a short distance above the horizontal partition, said conduit having an outlet opening above said barrier and a return inlet opening below said barrier and above the horizontal partition, whereby condensate flowing in said conduit is caused by said barrier to discharge through said outlet onto said horizontal partition and to return to the conduit below the barrier through said return inlet opening.
